UNITED STATES PATENT OFFICE

104,464

DESIGN FOR A ROAD MARKER

Louis A. McCarthy, Minneapolis, Minn.

Application August 14, 1936, Serial No. 64,410

Term of patent 3½ years

To all whom it may concern:

Be it known that I, Louis A. McCarthy, a citizen of the United States, residing at Minneapolis, in the county of Hennepin and State of Minnesota, have invented a new, original, and ornamental Design for a Road Marker, of which the following is a specification, reference being had to the accompanying drawing, forming part thereof.

Fig. 1 is a perspective view of a road marker showing my new design; and

Fig. 2 is a perspective view of the opposite side thereof.

I claim:

The ornamental design for a road marker, as shown.

LOUIS A. McCARTHY.
